To all whom it may concern:

Be it known that I, Herman E. Figure 1 is a front elevational view of a casket handle showing my new design.

Figure 2 is an end elevational view.

Figure 3 is a cross-sectional view taken along the line 3—3 of Fig. 1.

The design is especially characterized by the external contour of the cross bar forming the handle proper including the flat surfaced central rib *a*, the adjacent flat stepped surfaces *b*, and the convexly curved edge surfaces *c*.

I claim:

The ornamental design for a casket handle substantially as shown and described.
